UNITED STATES PATENT OFFICE.

FRANCIS THOMAS HEATLY, OF CAMANCHE, IOWA.

TABLE ATTACHMENT FOR CHAIRS OR BEDS.

SPECIFICATION forming part of Letters Patent No. 605,100, dated June 7, 1898.

Application filed October 19, 1897. Serial No. 655,707. (No model.)

To all whom it may concern:

Be it known that I, FRANCIS THOMAS HEATLY, a citizen of the United States, residing at Camanche, in the county of Clinton 5 and State of Iowa, have invented a new and useful Table Attachment for Chairs or Beds, of which the following is a specification.

This invention relates to attachments for beds, chairs, and the like, which provide a 10 table, rest, or support, according to the purpose required.

The intent of this invention is an attachment which can be turned to any position and tipped to any angle in any of the 15 adjusted positions, thereby securing a great range and variety of adjustment to meet all demands of an attachment of this kind. In addition the attachment can be moved vertically, laterally, or swung horizontally and 20 can be secured to a chair or bed in any desired position.

For a full understanding of the merits and advantages of the invention reference is to be had to the accompanying drawings and the 25 following description.

The improvement is susceptible of various changes in the form, proportion, and the minor details of construction without departing from the principle or sacrificing any of 30 the advantages thereof, and to a full disclosure of the invention an adaptation thereof is shown in the accompanying drawings, in which—

Figure 1 is a front view of a rocking-chair, 35 showing the invention in position. Fig. 2 shows the invention applied to the side rail of a bed. Fig. 3 is a detail view in elevation of the table, rest, or support, showing the universal joint between it and the standard. 40 Fig. 4 is a longitudinal section of the ball-socket clamp. Fig. 5 is a detail view in perspective of the clamp for attaching the device to a chair, bed, or other article.

Corresponding and like parts are referred 45 to in the following description and indicated in the several views of the drawings by the same reference characters.

The attaching-clamp consists of a bar or plate 1, having lateral extensions 2 and 3, 50 which constitute jaws to extend upon opposite sides of the part to which the device is to be attached. The jaw 3 is thicker than

the jaw 2 and has a threaded opening 4 to receive a binding-screw 5, by means of which the clamp is secured to the article to which it is desired to apply the attachment. An extension 6 is disposed at right angles to the jaw 3 and is in the same plane therewith, and is provided with an opening 7 to receive an arm of the right-angled standard 8, which is secured in an adjusted position by a clamp-screw 9, let into a threaded opening 10, intersecting with the opening 7. An opening 11 is formed lengthwise of the bar or plate 1, at right angles to the opening 7, and is designed 65 to receive an arm or member of the standard 8, which is secured therein when properly adjusted by means of a clamp or binding screw 9, let into a threaded opening communicating with the said opening 11. When 70 the clamp is applied to the arm of a chair or similarly-arranged part, as indicated in Fig. 1, the standard is adjustably secured in the opening 11; but when the clamp is attached to the rail of a bed or other part in like position the standard is secured in the opening 7, as clearly indicated in Fig. 2.

The table, rest, or support 12 may be of any desired construction, according to its use. When intended as a child's seat, it will be constructed to give proper support to the child, and when designed for a table it will be of suitable dimensions and outline, and when used as a book-rest or writing-table it will be provided at one edge with a foot or ledge to 80 retain the book in place when the rest is tilted to the desired angle to suit the comfort of the user. A ball 13 is secured centrally of the support or rest 12 by means of a plate 14, thereby admitting of the load being equally 85 distributed thereon.

The ball-socket clamp is of tubular form, and is composed of an end sleeve 15, an end clamp 16, and an intermediate ball-socket 17 for the reception of the ball 13. The clamp 95 end 16 is split longitudinally, and the separated portions are drawn together by clamp-screws 18, whereby the ball 13 is gripped with sufficient force to secure the support 12 in an adjusted position. The stem connecting the 100 ball 13 with the plate 14 passes through an opening 19 in a side of the socket, said opening being sufficiently large to admit of the support 12 being tipped to any angle desired

within the range or scope of the parts. The sleeve 15 receives an arm of the standard 8, and the latter is slidable therein and adapted to receive a rotary adjustment, whereby the support 12 may be moved in or out or turned on the standard, as required. A binding-screw 20, let into a threaded opening in the side of the sleeve, is adapted to secure the standard when adjusted.

10 It will be readily understood that the support 12 can be adjusted vertically, laterally, swung horizontally, and be tilted to any angle in any of the various adjustments, thereby admitting of a varied and great range of movement so as to meet all requirements.

15 A collar 21, provided with a binding-screw, is adjustable on the standard 8, and is moved to a position so as to rest upon the uppermost part of the clamp, as shown in Figs. 1 and 2, to support the standard when the binding-screw 9 is loosened prior to turning the standard aside.

Having thus described the invention, what is claimed as new is—

In an attachment for chairs, beds, and the like, the combination of a support or rest, a ball applied thereto, a ball-socket clamp of tubular form comprising an end sleeve, an end clamp consisting of separated parts, and an intermediate ball-socket formed in the meeting faces of the separated parts of the end clasp, said ball-socket receiving the ball applied to the support or rest, clamp-screws connecting the separated parts of the aforesaid end clamp upon opposite sides of the ball-clamp to contract the ball-socket and grip the aforesaid ball and hold the support in an adjusted position, and a standard having an adjustable connection with the sleeve portion of the said socket-clamp, substantially as set forth.

In testimony that I claim the foregoing as my own I have hereto affixed my signature in the presence of two witnesses.

FRANCIS THOMAS HEATLY.
